US00D658602S

(12) **United States Design Patent**
Egawa et al.

(10) **Patent No.:** **US D658,602 S**
(45) **Date of Patent:** **** May 1, 2012**

(54) **LIGHT EMITTING DIODE MODULE**

(75) Inventors: **Kazuo Egawa**, Kanagawa (JP); **Yuichiro Takahara**, Kanagawa (JP); **Seiko Kawashima**, Kanagawa (JP); **Akiko Saito**, Kanagawa (JP); **Tsuyoshi Oyaizu**, Kanagawa (JP); **Takeshi Arimura**, Kanagawa (JP)

(73) Assignee: **Toshiba Lighting & Technology Corporation**, Kanagawa (JP)

(**) Term: **14 Years**

(21) Appl. No.: **29/375,124**

(22) Filed: **Sep. 17, 2010**

(30) **Foreign Application Priority Data**

Jun. 15, 2010 (JP) 2010-014655

(51) **LOC (9) Cl.** **13-03**

(57) **CLAIM**

The ornamental design for a light emitting diode module, as shown and described.

DESCRIPTION

FIG. 1 is a perspective view of a light emitting diode module showing our new design;

FIG. 2 is a front view thereof;

FIG. 3 is a rear view thereof;

FIG. 4 is a right side view thereof, the left side view being a mirror image of the right side view; and,

FIG. 5 is a top view thereof, the bottom view being a mirror image of the top view.
